CHILD'S TRAINING CHAIR

Amedeo Di Russo and Louis Ernest Charpentier, Leominster, Mass., assignors to Sportsmen's Plastics, Inc., Leominster, Mass., a corporation of Massachusetts

Filed May 19, 1964, Ser. No. 80,068

Term of patent 14 years

(Cl. D4—5)

FIG. 1

FIG. 2

Des. 200,190

PAGE 2

FIG. 3

FIG. 4

FIG. 5

FIG. 1 is a side elevational view of a child's training chair embodying our new design;

FIG. 2 is a front elevational view thereof;

FIG. 3 is a plan view thereof;

FIG. 4 is a rear view thereof; and

FIG. 5 is a bottom view thereof.

The side not shown is the same in appearance as the side shown.

The drawing is shaded to establish the contours of the new design.

The essential features of our new design reside in the solid line disclosure on the drawing.

We claim:

The ornamental design for a child's training chair, substantially as shown and described.
